(57) **CLAIM**

The ornamental design for a collapsible bag loading sleeve of the present invention, as shown and described.

DESCRIPTION

FIG. 1 is a perspective view of a collapsible bag loading sleeve of the present invention;

FIG. 2 is a front view thereof;

FIG. 3 is rear view thereof;

FIG. 4 is a left side view thereof;

FIG. 5 is a right side view thereof;

FIG. 6 is a top view thereof;

FIG. 7 is a bottom view thereof;

FIG. 8 is a perspective, partially collapsed view of the collapsible bag loading sleeve of the instant invention;

FIG. 9 is a perspective, collapsed view of the collapsible bag loading sleeve of the instant invention; and,

FIG. 10 is a perspective environmental view, illustrating the collapsible bag loading sleeve of the present invention in the open position inserted into, and maintaining a canvas bag in an open position.

The portions of the figures shown in broken lines illustrate unclaimed portions of the present invention and form no part of the claimed subject matter.
